UNITED STATES PATENT OFFICE.

WILLIAM HAMMANN, OF MILWAUKEE, WISCONSIN.

VENTILATOR.

No. 873,125.

Specification of Letters Patent.

Patented Dec. 10, 1907.

Application filed April 20, 1907. Serial No. 369,314.

To all whom it may concern:

Be it known that I, WILLIAM HAMMANN, a citizen of the United States, residing at Milwaukee, in the county of Milwaukee and 5 State of Wisconsin, have invented a new and useful Ventilator, of which the following is a specification.

The present invention relates to improvements in ventilators of that type adapted to 10 be arranged on the roof of halls, theaters, and other buildings, for permitting heated and foul air to escape and to insure a supply of fresh air, and it has for its object to provide an improved ventilator of this character 15 which is so constructed that the ventilators may be made of very light sheet metal that are capable of retaining their shape, and, furthermore, it has for its object to provide an improved damper or valve for controlling 20 the passage of air through the ventilator.

To these and other ends, the invention consists in certain improvements and combinations and arrangements of parts, all as will be hereinafter more fully described, the 25 novel features being pointed out particularly in the claims at the end of the specification.

In the accompanying drawings: Figure 1 is a central vertical section of a ventilator constructed in accordance with my present 30 invention. Fig. 2 represents a horizontal section on the line 2—2 of Fig. 1. Fig. 3 is a perspective view of a brace constructed from sheet metal.

Corresponding parts in the several figures 35 are indicated throughout by similar characters of reference.

The ventilator shown in the present embodiment of the invention comprises a tube or pipe 1 of suitable diameter and adapted to 40 be mounted on the roof of the building to which the ventilator is to be applied, this tube or pipe being of a length sufficient to support the ventilator at a sufficient height above the roof to permit a free circulation of 45 air. To the upper end of the tube or pipe and spaced at suitable distances around the circumference are a series of rigid braces or reinforcements, such as shown in detail in Fig. 3, these braces being composed of bar 50 iron or other suitable material of suitable thickness and width to afford them the desired rigidity, these braces each embodying an inner attaching portion 3 which extends vertically and is riveted or otherwise secured 55 to the upper end of the pipe, and opposite the attaching portion is a vertical portion 4

to which is riveted, or otherwise secured, an annular wind shield 5 that is composed of tin or sheet iron of relatively light weight, the wind shield thus provided having vertically 60 extending sides that are concentric with the axis of the central pipe 1. At the rear end of the attaching portion 3 of each brace is formed a lower storm shield support 6 to which is riveted, or otherwise secured, a 65 conical storm shield 7 having its sides extending obliquely relatively to the sides of the central supporting plate, an intermediate connecting portion 8 of each brace extending between the outer edges of the wind or 70 storm shields 5 and 7, respectively, to retain these parts firmly in their proper relative positions.

Extending outwardly from the upper portion of the attaching portion 3 of each brace 75 is a connecting portion 9, the outer end of the latter being extended in a direction upwardly and inwardly to form an upper storm shield support 10 to which the conical storm shield 11 is riveted or otherwise secured, the 80 latter being so located that its upper edge is spaced below the roof or top 12. The latter is conical in shape and is composed of relatively light sheet iron or tin, and it is supported in position by means of the connecting portions 13 and 14, the connecting portion 13 extending in a direction inwardly and upwardly from the upper end of the wind shield, and the connecting portion 14 extending upwardly from the upper edge of the 85 upper storm shield, the peripheral edge of the roof or top preferably projecting beyond the upper or smaller diameter of the upper storm shield to prevent the entrance of rain to the central draft or supporting pipe. These 90 braces may be formed either integral or of a single piece of metal of endless form, although it is preferable to form them of a single piece for the reason that it facilitates assembling of the ventilator. If so desired, the braces 100 for securing the wind and storm shields and the top to the supporting tube may be made up of sheet metal, a brace so constructed being shown in Fig. 3 of the drawings, and comprising a plate or body portion 30 adapted to extend radially of the ventilator when in position, the peripheral edges of the plate bent at right angles to its surfaces to form a set of attaching portions or flanges, the flange 31 serving as an attaching portion for 105 the wind shield 5, the flange 32 for the attachment of the top, the flanges 33 and 34

serving as attachments for the upper and lower storm shields, and the flanges 35 providing means for securing the brace to the supporting pipe, the intermediate flanges 36, 37 and 38 serving to stiffen the brace at points intermediate those parts attached to the elements of the ventilator. A brace constructed as above described may be made very cheaply as it can be punched and stamped into form from sheet metal by the use of dies, requiring very little metal.

Surmounting the top or roof is a cap 15 and beneath the cap and secured to the center of the roof or top is a guiding tube 16 which extends axially of the supporting or draft pipe and is held centered relatively thereto by means of a series of braces or stays 17 which are composed of bar iron having their outer ends secured to the inner side of the supporting pipe and are attached at their inner ends to the guiding tube, a suitable number of stays being spaced radially between the central guiding tube and the supporting pipe. Mounted to operate axially of the guiding tube is a damper or valve 18 which is composed, in the present instance, of upper and lower conical members 19 and 20, respectively, that are made of sheet metal of a suitable strength, the members being placed together with their concavities facing one another and are connected at their centers by means of a sleeve 21 which has a sliding fit on the guiding tube of the damper so that the damper or valve will operate vertically thereon. The outer edges of the conical members are secured in any suitable way, such as by riveting or folding, and the valve thus provided is adapted to cooperate with the upper end of the draft or supporting pipe to control the flow of air therethrough, and in order to insure a close fitting of the damper, the upper edge of the draft pipe is provided with a felt seat 22 on which the damper rests when in closed position, this felt seat in the present instance being formed of a strip having its longitudinal edges folded on the inner and outer sides of the draft pipe.

In order to facilitate the operation of the damper it is counterbalanced by a weight 23 which is guided to operate vertically within the guiding tube, a cord or chain 24 having an intermediate portion passing through an eye or pulley 25 on the weight, and having its ends attached to the damper at points on opposite sides of the guiding tube, and in order to effect an automatic closing of the damper in case of fire, fusible links 26 and 27 are interposed between the ends of the connecting cord and the damper to permit closing of the latter when the temperature within the ventilator exceeds a given limit.

The device may be so constructed that the counterweight is heavier than the damper, 65 in which case a cord can be attached to the

latter to effect its closing, or, if so desired, the weight of the damper may equal that of the counterweight, and the latter may be provided with an operating device such as a cord or rod 28 extending downwardly 70 through the lower end of the guiding tube, as shown, a lifting movement of the counterweight causing a closing movement of the damper and a downward movement of the counterweight causing an opening movement 75 of the damper. In order to minimize friction, the end of the balancing cords pass over relatively fixed pulleys 29 and 30 mounted within the cap 15, the latter serving to close the guiding tube and protect the 80 pulleys and other operating parts.

A ventilator embodying my present invention may be constructed of very thin or light sheet metal for the reason that the weight and strains to which the parts are 85 subjected is sustained by the reinforcing braces, the sheet metal serving mainly for the purposes of breaking the direct course of the wind striking the ventilator from the outside and to prevent entrance of rain, and 90 the like, and the improved form of damper not only centralizes the construction of the device, but it improves the circulation of air, for the reason that when it is in open position, it fills the space formed in the center 95 of the top cone and the lower conical surface of the damper serves as an angular deflector for directing the air passing outwardly through the spaces at the top and bottom of the upper storm shield, so that very little 100 suction is required to effect the discharge of the air.

What is claimed is:—

1. In a ventilator, the combination with a draft pipe, and a roof supported above the upper open end thereof, of a tube centered axially of the draft pipe, a valve arranged to coöperate with the draft pipe and having a sleeve guided to operate longitudinally of the said tube, a counterweight mounted to 110 operate vertically within the said tube, and operative connections between the counterweight and the valve whereby the former balances the latter.

2. In a ventilator, the combination with a supporting or draft pipe, and a top spaced above the upper end thereof and forming an exit for the air ascending the pipe, of a guiding tube arranged axially of the pipe, a damper guided to operate on said tube and to co-operate with the upper end of the draft pipe to control the flow of air therethrough, a counterweight guided to operate longitudinally within the tube, and operative connections between the counterweight and damper.

3. In a ventilator, the combination with a supporting or draft pipe, and a top mounted above the upper end thereof and forming an exit for air ascending the pipe, of a guiding

- tube arranged axially of the pipe, a damper guided to operate longitudinally of the tube and adapted to coöperate with the upper end of the pipe, a counterweight mounted to operate vertically within the guiding tube, a flexible cord having its ends attached to the damper, and loosely engaging the weight at an intermediate point and pulleys mounted in the top for guiding the cord.
- 10 4. In a ventilator, the combination with a supporting or draft pipe, and a top spaced above the upper end thereof, of a guiding device arranged between the top and the supporting pipe, a damper mounted to operate vertically of said guiding device and adapted to coöperate with the upper end of the pipe to control the passage of air therethrough, a counterweight for normally supporting the weight of the damper, flexible connections attached to the counterweight and extending to the underside of the damper; and fusible links secured to the underside of the damper and attached to the flexible connections for relieving the supporting action of the weight.
- 20 5. In a ventilator, the combination with a supporting or draft pipe, and a conical top

spaced above the upper end thereof, of a guiding tube connected at its upper end to the top and having stays operatively connecting its lower end to the pipe, a damper mounted to operate longitudinally of the guiding tube and adapted to coöperate with the upper end of the pipe, embodying a pair of conical sheet metal members placed together with their concavities facing one another, and a central sleeve connecting the conical members, a counterweight mounted to operate longitudinally of the guiding tube, flexible connections attached to the counterweight, an operating device connected to the counterweight and extending through the lower end of the guiding tube, and fusible links arranged at the underside of the damper and connecting the latter to the flexible connections.

In testimony that I claim the foregoing as my own, I have hereto affixed my signature in the presence of two witnesses.

WILLIAM HAMMANN.
